DESIGN FOR A PERFUME BOTTLE OR SIMILAR ARTICLE

Joseph S. Stein, Chicago, Ill., assignor to Lucien Lelong, Inc., Chicago, Ill., a corporation of Illinois

Application April 20, 1936, Serial No. 62,213

Term of patent 3½ years

To all whom it may concern:

Be it known that I, Joseph S. Stein, a citizen of the United States, and a resident of the city of Chicago, county of Cook, and State of Illinois, have invented a new, original, and ornamental Design for a Perfume Bottle or Similar Article, of which the following is a specification, reference being had to the accompanying drawing, forming a part thereof.

On the drawing:

I claim:

The ornamental design for a perfume bottle or similar article, as shown.

JOSEPH S. STEIN.
